UNITED STATES PATENT OFFICE.

JOHN L. HEFFNER, OF PEORIA, ILLINOIS.

UPHOLSTERING APPARATUS.

SPECIFICATION forming part of Letters Patent No. 651,486, dated June 12, 1900.

Application filed June 3, 1898. Serial No. 682,487. (No model.)

To all whom it may concern:

Be it known that I, JOHN L. HEFFNER, a citizen of the United States, residing at Peoria, in the county of Peoria and State of Illinois, have

5 invented certain new and useful Improvements in Upholstering Apparatus; and I do hereby declare that the following is a full, clear, and exact description of the invention, which will enable others skilled in the art to 10 which it appertains to make and use the same.

This invention relates to upholstering apparatus for use in producing continuously-tufted cushions, pads, or cushion-sections to be employed for covering couches, chairs, and 15 the like.

The objects of my invention are to facilitate the making of the padding by first providing a machine of the character described with means for quickly and easily changing 20 the depth of the mold or former in which the padding is made, whereby any thickness of padding may be constructed without the necessity of employing forming-blocks of various heights; secondly, to provide better means 25 for tying or securing the padding at intervals to give it its form and so retain it, and, lastly, to provide means for simultaneously operating a series of lids or covers for the former compartments.

30 In the accompanying drawings, Figure 1 is a perspective view of my entire machine. Fig. 2 is a plan view of a portion of the machine shown in Fig. 1. Fig. 3 is a partial sectional end elevation of the machine, showing 35 means for adjusting the bottom thereof. Fig. 4 is a perspective view of a section of the machine, showing the form of a dividing-partition. Fig. 5 is a perspective view of independent former-blocks and an adjustable bot- 40 tom of the former cut in sections. Fig. 5^a is a perspective view of the form of padding made by this machine. Fig. 6 is a sectional end elevation of a modified form of my device, showing means for imparting vertical move- 45 ment to the sides of the mold or former.

I am perfectly aware that devices of the character herein described for making single length of tufting have been used heretofore and that they have been provided with various devices for more perfectly forming the padding. I am also aware that several methods of providing partitions to form trays have

been employed, as well as slots for tying or sewing the tufts; but the forms which I shall describe are entirely new and have many 55 advantages over the older forms.

It has been customary to change the depth of the mold or former by inserting blocks of various heights in the bottom of the compartments; but this is a clumsy and unsatisfactory 60 method.

My improvements may be fully understood from what follows.

A represents the sides of the mold or former, which are supported by the standards B and 65 held rigidly with relation to each other by the yokes C C. A number of vertical slots E are cut in the sides in the manner shown and extend from the top to the bottom. A vertical partition or wall F, secured in each slot, ex- 70 tends across the machine to the opposite slots and are there secured. A space is left between the partitions and the adjoining section sufficient to permit the passage of a cord or wire for tying the tufts. A portion of the 75 entire length of the bottom of the mold is cut out and a false bottom H made to fit therein, capable of vertical adjustment by means of a thread-bar J at each end of the machine. A crank is provided for driving either one or 80 both of said bars, and a driving-chain serves to impart motion to both alike by means of the sprockets K. By this means the false bottom H is moved vertically on a perfect level at all times. The thread-bars have 85 their bearings in the yokes C, as shown, and the upper extremities carry the housings or sockets H', secured to the adjustable portion H described. A series of blocks I is secured to the bottom, a space being left be- 90 tween each block to permit raising and lowering without interfering with the partitions F. It will be seen that the partitions or division-walls F are cut out to leave the space F'. This is to permit the portion H to rise 95 freely to any height. Removable blocks G are provided for each of the compartments, and these may be of any desired shape. I provide a lid or cover M for each of the said compartments or trays; but they are all 100 mounted by arms M' upon a shaft N', held in brackets N on the side of the mold, and move in a body. A lever O serves to operate the covers thus located, and a pin O', Fig. 2, en-

gages openings or depressions in a quadrant P for locking the lids or covers in the extreme positions. In Fig. 6 I show another manner in which my device may be operated with good results. The bottom H in this case is held firmly by the standards or legs B, and the sides A are permitted to move vertically. The results are identical with those of the first form and merely show how the construction may be altered.

In operation of the form shown in Fig. 1 the bottom H is elevated to the desired height by the thread-bars and the tying cord or wire is placed within the slots E upon the bottom either in single lengths or for convenience in 15 a zigzag manner through each successive pair of slots, as shown in Fig. 2, using in this case a single strand of the tying medium. The device is now packed with padding material 20 and the strings are tied to form the tufts. It is obvious that if the single length of tying material is employed it is severed at each side to form single lengths before being tied. It will be seen that a very important part of 25 my invention is the use of some means other than the old blocks before mentioned for quickly and easily changing the depth of the mold for making different thicknesses of padding; and this, at least in so far as I am aware, 30 has not been used in machines of this character. Another point in my device is the mounting of all the lids or covers M upon a common shaft and all moved simultaneously instead of individually, as heretofore. It is 35 evident that the device may be used without the covers, as by placing the material within the mold and holding it with the hand it may be tied as in the first instance.

The partitions may be dispensed with, if 40 desired, and simply tying cords or wires may be used to accomplish as good results as before. Any other means of manipulating the adjustable bottom than that shown and described may be employed.

45 The partitions instead of being slotted, as shown, may be extended entirely to the bottom of the former and the adjustable portion H instead of being made in a continuous length may be divided into as many sections 50 as there are compartments, and such sections may be individually mounted upon arms which would reach up into the mold and carry the attached sections. Furthermore, so mounted the entire series may be moved together or moved one at a time, each being 55 free of its neighbor, whereby each tuft could be made of a different thickness to suit the wants of the operator. The adjusting means for changing the thickness of the tufting may 60 be transferred to the top of the machine, or, in other words, the covers could be arranged to descend within the mold and the bottom remain fixed and the result be just as effective. The sides A may also be adjustable, so that 65 the width of the tufted sections may be altered to suit special requirements.

For certain kinds of work the partitions

may be dispensed with and the cord or other tying medium may be employed to contract the padding at various points in its length, 70 thus making the padding into biscuit form, as in Fig. 2.

I do not intend to confine myself to any particular construction, and various changes may be made to produce a valuable machine in 75 the hands of the user.

Having thus described my invention in its various details, I broadly claim—

1. In an upholstering apparatus, a mold or former comprising a series of tufting-compartments, partitions within the mold for separating the compartments, slots in the sides of the mold or former running the full depth thereof adjacent to the said partitions, means for varying the depth of the mold, and simultaneously-operated lids or covers for the said compartments for the purposes set forth. 85

2. In an upholstering apparatus, a mold or former comprising a series of tufting-compartments, a series of simultaneously-operated covers or lids, slots in the sides of the mold running the full depth of the mold, said slots being in line with the spaces between the covers, partitions occupying position within the slots, an opening or slot in each of 90 the partitions for the purposes set forth and means for increasing or decreasing the depth of the mold for the purposes set forth. 95

3. In an upholstering apparatus, a mold or former comprising a series of tufting-compartments, partitions for separating them, slots in the sides of the mold in line with the divisions of the several compartments, and a vertically-adjustable bottom for the mold or former substantially as described. 100

4. In an upholstering apparatus, a mold or former comprising a series of tufting-compartments, partitions for separating them, slots in the sides of the mold in line with the divisions of the several compartments, a vertically-adjustable bottom for the mold and a series of removable blocks therefor substantially as set forth and described. 110

5. In an upholstering apparatus, a mold or former comprising a series of tufting-compartments, partitions for separating them, slots in the sides of the mold in line with the divisions of the several compartments, a vertically-adjustable bottom for the mold, a series of removable blocks therefor, and simultaneously-operated covers for the several compartments substantially as set forth and described. 115

6. In an upholstering apparatus a mold or former comprising a series of tufting-compartments, a lid or cover for each compartment, slots in the sides of the mold for tying purposes as described, partitions within the mold and a bottom capable of vertical adjustment for the purpose set forth. 125

7. In an upholstering apparatus comprising a mold or former, the sides thereof, slots in the sides within which to lay tying medium and an adjustable bottom for the mold or

- former, upon which to lay the said tying medium and tufting material as set forth.
8. In an upholstering apparatus, a mold, or former consisting of the sides A, slots E therein, transverse partitions F in the slots forming compartments, recesses F' in the partitions, in combination with an adjustable bottom adapted to raise and lower within the former, thread-bars suitably journaled on the former for manipulating the bottom, a wheel on each thread-bar and driving means on the wheels for causing the bars to move alike when one of them is turned substantially as and for the purposes described and shown.
- 15 9. In an upholstering apparatus, a mold, or former consisting of the sides A, slots E therein, transverse partitions F in the slots forming compartments, recesses F' in the partitions, covers for the compartments, in combination with an adjustable bottom adapted to raise and lower within the former, thread-bars suitably journaled on the former, for manipulating the bottom, a wheel on each thread-bar and driving means on the wheels for causing the bars to move alike when one of them is turned substantially as and for the purposes described and shown.
- 25 10. In an upholstering apparatus, a mold, or former consisting of the sides A, slots E therein, transverse partitions F in the slots form-

ing compartments, recesses F' in the partitions, forming-blocks for the compartments in combination with an adjustable bottom adapted to raise and lower within the former, a thread-bar suitably journaled on the former for manipulating the bottom, a wheel on each thread-bar and driving means on the wheels for causing the bars to move alike when one of them is turned substantially as and for the purposes described and shown.

11. In an upholstering apparatus, a mold, or former consisting of the sides A, slots E therein, transverse partitions F in the slots forming compartments, recesses F' in the partitions, covers for the compartments, forming-blocks for the compartments in combination with an adjustable bottom adapted to raise and lower within the former, thread-bars suitably journaled on the former for manipulating the bottom, a wheel on each thread-bar and driving means on the wheels for causing the bars to move alike when one of them is turned substantially as and for the purposes described and shown.

In testimony whereof I affix my signature in presence of two witnesses.
